INVENTOR
Hillyard A. Starr
By
Alexander T. Dowell
Attorney

It is hereby certified that the name of the assignee in Letters Patent No. 35,542, granted December 31, 1901, upon the application of Hillyard Augustus Starr, of Sherman Heights, Tennessee, for a "Design for a Fireplace-Grate," was erroneously printed "The Chattanooga Supplement and Manufacturing Company," whereas said name should have been printed *The Chattanooga Implement and Manufacturing Company*; and that the said Letters Patent should be read with this correction therein that the same may conform to the record of the case in the Patent Office.

Signed, countersigned, and sealed this 14th day of January, A. D., 1902.

[SEAL.]

F. L. CAMPBELL,
Assistant Secretary of the Interior.

Countersigned:

F. I. ALLEN,
Commissioner of Patents.

UNITED STATES PATENT OFFICE.

HILLYARD AUGUSTUS STARR, OF SHERMAN HEIGHTS, TENNESSEE,
ASSIGNOR TO THE CHATTANOOGA SUPPLEMENT AND MANUFACTURING COMPANY, OF EAST CHATTANOOGA, TENNESSEE.

DESIGN FOR A FIREPLACE-GRATE.

SPECIFICATION forming part of Design No. 35,542, dated December 31, 1901.

Application filed November 18, 1901. Serial No. 82,803. Term of patent 7 years.

To all whom it may concern:

Be it known that I, HILLYARD AUGUSTUS STARR, a citizen of the United States, residing at Sherman Heights, in the county of Hamilton and State of Tennessee, have invented and produced a new and original Design for Fireplace-Grates, of which the following is a specification, reference being had to the accompanying drawing, forming part thereof, which shows a front view of the fireplace-grate.

The design embodies a rectangular frame which is made of exterior dimensions suited to various fireplaces. The top and vertical side pieces A and B of this frame have a fretted background, as indicated at C, formed of raised lines intersecting at right angles. The lower portion of the top bar A is swelled outwardly, as at D, and is further ornamented by the oppositely-extending sprays or foliations d. The outer and inner edges of parts A B are also beaded, as at a b. The lower part or ash-screen E of the frame is also swelled outwardly and is provided with two

horizontal rows of foliations F, forming an open foliated grating. Above this lower portion E and the fire-grate bars G is a horizontal basket or grating H, formed of a series of inverted foliated heart-shaped portions I, between which are horseshoe-shaped portions I'.

The leading and material features of the design are the frame members A and B, the ash-screen or foliated member E, and superimposed foliated member or basket H, substantially as shown and described.

Having thus described my invention, what I therefore claim as new is—

The design for a fireplace-grate as herein shown and described.

In testimony whereof I have signed my name to this specification in the presence of two subscribing witnesses.

HILLYARD AUGUSTUS STARR.

In presence of—

E. H. SHOLAR,
D. T. RICHARDS.
